UNITED STATES PATENT OFFICE.

WILL A. SHIMER, OF ROCHESTER, NEW YORK.

PORTABLE TELEPHONE.

No. 821,753.

Specification of Letters Patent.

Patented May 29, 1906.

Application filed October 3, 1905. Serial No. 281,156.

To all whom it may concern:

Be it known that I, WILL A. SHIMER, a citizen of the United States, residing at Rochester, in the county of Monroe and State of New York, have invented new and useful Improvements in Portable Telephones, of which the following is a specification.

This invention relates to telephone apparatus.

One object of the invention is to provide a desk-phone embodying such characteristics that it may be rendered portable to permit the shifting of the phone, including the receiver and transmitter mechanism, from one place to another without placing strain upon the conductor-cord while in use.

Another object resides in the provision of a desk-telephone constructed and arranged to permit the movement of the phone and its conductor-cord away from its fastening different distances within a predetermined radius.

A still further object is to provide a desk-telephone of such nature that it and its conductor-cord may be shifted from one place to another and so constructed, arranged, and associated with each other that the conductor-cord may be automatically wound within the base of the instrument and locked automatically against winding therein, according to the disposition of the phone-receiver.

With these and other objects in view the present invention consists in the combination and arrangement of parts, as will be hereinabove more fully described, shown in the accompanying drawings, and more particularly pointed out in the appended claims, it being understood that changes in the form, proportion, size, and minor details may be made within the scope of the claims without departing from the spirit or sacrificing any of the advantages of the present invention.

In the drawings, Figure 1 is a vertical sectional view of a desk-telephone, illustrating my improvements. Fig. 2 is a bottom plan view. Fig. 3 is a horizontal sectional view.

Referring now more particularly to the accompanying drawings, the reference character 1 designates a bell-shaped or other form of base provided with a hollow post 2, at the upper end of which latter is mounted the usual form of transmitter 3. The receiver-hook 4 is of the usual form and pivotally mounted with respect to the post in the same manner as is common with all devices of this character.

Arranged within the base 1 is an induction-

coil 5, which is held in proper position by means of a suitable bracket 6, secured to the free end of the post 7, depending from the top of the post off from one side of the aforesaid hollow post 2. Disposed parallel with the induction-coil 5 is a non-insulating shelf 8, associated with which latter are a number of any form of binding-posts 9. This non-insulating shelf 8 is supported within the base 1 by means of posts 9^a, depending from the top of the latter, and the said binding-posts have associated therewith and with the induction-coil suitable conductor-cords *a*. As these are minor features of the invention and the features themselves are common in the art, except as regards the particular disposition thereof, I believe that further description is unnecessary.

Extending across and within the base 1 is a metallic bar 10, provided intermediate its end with a perforation 11. This perforation 11 is adapted to receive the reduced end 12 of a rotatable shaft 13 of a spring-actuated reel 14, and the said reduced end 12 of this shaft 14 is adapted to contact with the aforesaid bracket 6, with the opposite end of the shaft fixedly mounted at the point of intersection of the metallic bars of strips 15 and 16, which cross each other intermediate their ends. If preferred, a solid plate (not shown) could be used instead of the said strips 15 and 16. The reel just alluded to consists of upper and lower disks 17 and 18, which are held in spaced relation by a spring inclosing band 19, which is of such cross-sectional diameter as to lie considerably within the peripheries of the said disks, the said band 19 being held in the manner stated through the instrumentality of connecting-posts 20, arranged exteriorly thereof. The lower disk 18 is in spaced relation with the aforesaid cross bars or strips 15 and 16, there being a spacing member 21 therebetween. The periphery of this lower disk 18 is smooth and, with the aforesaid cross bars or strips 15 and 16, serves as the bottom of the base 1, the opposite bent ends *d* of the crossing bars or strips 15 and 16 having screw-threaded perforations for the reception of screws *e*, passed through the lower edge of the base to hold the strips and reel in proper position with reference to the base.

Mounted in any suitable manner upon the upper face of the upper disk 17 of the reel 14 are brass or other rings 23 and 24, which surround the upper end of the aforesaid shaft 13 in spaced relation thereto and to themselves.

These rings are designed to have engagement with the free bent ends *b* of the contact-fingers 25 and 26, respectively, which latter are secured in any suitable manner to the aforesaid bar 10 and insulated therefrom by means of the non-conducting material 27. These fingers 25 and 26 are of spring material and fixedly secured at one of their ends by suitable binding-posts 28 to the said bar 10, and these posts 28 are connected up in any suitable manner with the aforesaid conductor-cords within the base.

It has been stated in the foregoing that the reel 14 is a spring-actuated one, and reference to the drawings will disclose that a helical winding-spring 29 has one of its ends fixedly connected to the aforesaid shaft 13, with its opposite end fixedly connected to the inner face of the aforesaid spring inclosing-band. The spring inclosing-band has secured in any suitable manner to its upper face the conductor-cord 30, which latter passes through the insulated opening *c* of the base 1 and has its branched ends connected to the framework 31 of the apparatus by means of suitable binding-posts 32. By reason of the spring 29 the conductor-cord 30 is normally held within the base between the band 19 and the disks 17 and 18. However, the conductor-cord 30 is of such length as to permit the phone to be moved from close proximity to the fixed framework 31 to a distance—say, for instance, of twenty-five feet, more or less. Therefore if it should be desired to move the phone from one desk to another or to a distant part of an office or other room it would simply be necessary to grasp the post 2 and carry the phone to said distant point, as may be desired, such movement of the phone lengthening the conductor-cord 30 against the action of the winding-spring 29. When the phone has thus been moved and it is desired to send or receive a message, the receiver (not shown) is removed from the receiver-hook 4. When the receiver is taken from the hook, the reel is locked against reverse movement in a manner to be now described.

In order to prevent the above-mentioned reverse movement of the reel, I pivotally connect to the finger 34 of the receiver-hook 4 a bent or other rod 35, which extends downwardly through the hollow post 2 and terminates within the base 1. In other words, the rod 35 is pivotally connected at its upper end to the receiver-hook 4 and at its lower end pivotally connected to an angular rocking lever 36, mounted between the legs 37 and 38 of the bracket 39, whose opposite end 40 is bent outwardly from engagement with the interior of the base and then downwardly and provided with an eye 41 to form a guide for the sliding movement of the arm 42, which has one of its ends pivotally connected, as at 43, to the aforesaid rocking lever 36,

with its opposite end arranged for engagement with the outer free end of the spring-dog 44, which latter has one of its ends fixedly connected to the interior of the base 1. Now since the spring-dog 44 is normally in engagement with the teeth 22 of the upper disk 17 the reel is held against backward movement. Obviously the lower disk could have teeth in its periphery instead of the upper disk. However, just as soon as the receiver is placed upon the receiver-hook 4 the latter is pressed downwardly, thereby drawing the rod 35 upwardly and throwing the arm 42 against the free end of the spring-dog 44, whereby the latter is moved out of engagement with the teeth 22 of the disk 17, permitting of a rewinding of the conductor-cord 30 as the result of the action of the helical spring 29. Of course the spring 29 is not of such tension as to pull the phone from off a desk in the event that it was not desired to return the phone immediately toward the framework 31.

The operation of the reel in the manner stated and the consequent lengthening of the conductor-coil 30 is one of the essential features of my invention; but there is another feature worthy of consideration in that I am enabled by reason of the crossing-bar or strips 15 and 16, which are fixedly connected to the shaft 13, to rewind the spring in the event that it should become unwound in removing the reel from the base 1. It will be noted that I provide alining perforations 46 and 47 in the upper and lower disks 17 and 18, respectively, for the insertion of any suitable element, (not shown,) which latter when inserted will prevent accidental unwinding of the spring by reason of the engagement of the crossing bars or strips therewith. Another essential feature of my invention resides in the fact that the conductor-cord will not become twisted, as do the conductor-cords of the present arrangement of desk-phones.

What is claimed is—

1. In combination with telephone apparatus, a hollow base, a post mounted upon the base, a receiver-hook pivotally mounted at the upper end of the post and having one end extending into the post, a reel mounted in said base for rotation therein, a conductor-cord passed into the base and connected to said reel, said cord being unwound from the reel upon movement of the base, means for preventing backward movement of the reel when rotated by movement of the base, and means connected with the receiver-hook to release the reel and permit the reverse movement of the latter upon placing the receiver upon the said hook.

2. A desk-telephone attachment, comprising a hollow base and post, a receiver-hook pivotally mounted upon the post, a spring-actuated reel within said base, the reel includ-

ing upper and lower disks, one of the disks having a toothed periphery, a conductor-cord passed into the base and connected to the reel whereby the latter may be rotated against the action of its spring by a pull upon said cord, a dog arranged within the base to engage the teeth of the upper disk to hold the reel against backward movement to relieve said cord of strain when pulled outwardly of the base, and a connection between the receiver-hook and the base for engagement with the said dog to release it from engagement with the toothed edge of the upper disk and permit winding of the reel.

15 3. A desk-telephone attachment comprising a hollow base and standard, a spring-actuated reel arranged within the base, a receiver-hook mounted at the upper end of the standard and extending into the latter, a conductor-cord passing into the base and connecting with the said reel whereby the latter may be rotated by a pull upon said cord to move the attachment from one place to another, means engaging the reel to hold it against backward movement when rotated by a pull upon the cord, a connection between the receiver-hook and the base of the attachment for engagement with the said reel, and means adapted for engagement with the holding means to disengage it from the reel to permit backward movement of the latter.

4. A desk-telephone attachment comprising a hollow base and standard, a receiver-hook for the support of a receiver, a conductor-cord passing into the base and secured therein to permit shortening or lengthening

of the cord, a rod connected with the receiver-hook and arranged within the base and standard, and a connection between the rod and the cord to relieve the latter of strain and prevent twisting thereof when pulled outwardly of the base.

5. A desk-telephone attachment comprising a hollow base and standard, an induction-coil mounted within the base, a shelf mounted within the base in alignment with the induction-coil, a reel mounted within the base beneath the induction-coil and shelf, electrical conductor-cords connecting the induction-coil and shelf, conductor elements between the reel and shelf, said reel including upper and lower disks, one of the disks having a toothed periphery, a conductor-cord passed into the base and engaged with the reel whereby the latter may be rotated in one direction by exerting a pull upon the conductor-cord, a dog engaging the toothed periphery of one of the said disks to hold the reel against backward movement when rotated by exerting a pull upon the last-named cord, 60 a receiver-hook pivotally mounted upon said standard, and a rod connected with said hook and having its lower end arranged for engagement with said dog to permit backward movement of the reel upon a downward 65 movement of said hook.

In testimony whereof I affix my signature in presence of two subscribing witnesses.

WILL A. SHIMER.
